BIT HOLDER FOR TRAPEZOIDAL TYPE CUTTER BITS AND MANUFACTURE THEREOF

Claude B. Krekeler and Armin O. Bruestle, Cincinnati, Ohio, assignors to The Cincinnati Mine Machinery Co., Cincinnati, Ohio, a corporation of Ohio

Application October 6, 1955, Serial No. 538,942

11 Claims. (Cl. 262—33)

The invention relates to the provision of bit holders, particularly for the so-called trapezoidal type of mining machine cutter bits of throw-away character. The bit holders are usually employed in sockets formed in links of a mining machine cutter chain, although they may be employed in connection with moving elements of other types of mining machinery.

It is an object of the invention to provide a cutter bit holder having a number of particular advantages, among which may be mentioned the provision of an adequate flat stop or abutment for engaging a face of the cutter bit and sustaining the main cutting thrusts, together with elements surrounding other portions of the cutter bit and coacting with the abutment to give a wedging action such that the bit will be adequately held by the holder in cutting position so long as the withdrawal of the bit in the direction of its major axis is prevented. The provision of adequate clearance for an unused bit point is also a feature of the invention.

Another object of the invention is the provision of a bit holder structure having the above advantages which can be made more cheaply, and in operations requiring fewer steps.

These and other objects of the invention, which will be set forth hereinafter or will be clear to one skilled in the art upon reading these specifications, are accomplished by that structure and arrangement of parts and in that procedure of which certain exemplary embodiments will now be described. Reference is made to the accompanying drawings wherein:

Fig. 1 is a partial elevational view of a cutter chain including a socket link and set screw, a bit stop, a bit holder, and a cutting bit.

Fig. 2 is a side elevation of one form of the bit holder with a bit in place therein.

Fig. 3 is a perspective view of a trapezoidal bit.

Fig. 4 is a front elevation of the bit holder of Fig. 2 with the bit removed.

Fig. 5 is a view of the holder similar to that of Fig. 2 but with parts broken away along the section line 5—5 of Fig. 4 to show interior construction.

Fig. 6 is a similar view of a bit holder in an initial stage of manufacture.

Fig. 7 is a similar view showing a later stage of manufacture.

Fig. 8 is a similar view of another form of bit holder in an initial stage of manufacture.

Fig. 9 shows the same bit holder in a later stage of manufacture.

Fig. 10 is a perspective view of an anvil member.

A trapezoidal bit of known form is illustrated at 1 in Fig. 3. The bit holder is formed, as is usual in the art, by cutting suitable steel rod stock of generally diamond shape cross-section along slantwise, transverse, nonparallel planes. After manufacture the bit is tempered to give it cutting qualities; and it may be tipped with hard alloy if desired. It will be seen to have oppositely directed cutting points 2 and 3 which are designed for alternative

2

use. After both cutting points are worn to the extent that efficient cutting can no longer be done, the bit is discarded. The term "trapezoidal" refers to the shape of the bit in side elevation, but should not be regarded as a term of express limitation. Bits which are triangular in side elevation may be employed; and variations in the shapes of the cutting points may be made. The term, however, is indicative of a recognized class of cutting bits to which this invention primarily pertains.

10 As illustrated in Figs. 2, 4 and 5, the exemplary bit holder of this invention is a unitary metallic body having a shank 4 and a head 6. The head is hollow, providing a central space into which an end of the trapezoidal bit may be passed. In the exemplary structure, the hollow

15 is generally of triangular cross-section. It is, however, characterized by a basal flat or upstanding abutment 7 which serves to engage a face 8 of the cutting bit. The head 6 is also characterized by integral portions 9 and 10 which surround other portions of the bit to hold it in place and provide a wedging action in cooperation with the abutment 7. It will be evident that one of the cutting points of the bit extends into and in some instances through the bit holder. It is necessary to provide clearance for this cutting point.

20 25 The bit holder of the invention is most conveniently and cheaply made by drop forging operations. These are operations in which a blank of suitable metal is placed in a die and shaped therein under pressure by one or more power operated plungers. In some instances a single

30 plunger may be employed to accomplish all of the shaping, depending on the nature of the blank and the nature of the mold. The shaping is done with the metal blank at elevated temperature, as is well known in the art. Whether one or a series of plungers is employed, is not a

35 necessary limitation of the invention. It is sufficient to point out that, as illustrated in Fig. 6, the blank is externally shaped to the required configuration by drop forging and is also provided with an interior hollow in the head (indicated at 11 in Fig. 6) which hollow extends generally transversely of the shank, is shaped to its final form, and is complete with the abutment means 7. The hollow, as illustrated in Fig. 6, however, does not supply the clearance for the lower cutting point of the bit.

40 45 This clearance, in accordance with the invention, is supplied by a simple operation of drilling into the opposite end of the head 6 a hole, somewhat larger than the inner end of the orifice 11, to a depth such that the drilled hole 12 meets and joins with the orifice 11, as illustrated in Fig. 7. This may be accomplished by means of a drill 13 suitably power actuated, the holder being held in a suitable jig during the drilling operation.

50 55 The manner in which the bit 1 seats in the bit holder will be abundantly clear from Figs. 2 and 5. In Fig. 1 there is shown a portion of a mining machine cutting chain of known form, having a socket link 14, a portion of which is laterally prolonged, as at 15, to provide a socket element. The socket element is perforated as at 16 to accept the shank 4 of the bit holder which is held in place by a set screw 17. Forward and rear portions

60 65 18 and 19 of the prolongation preferably extend upwardly to provide abutments. An anvil member 20 is provided at the front of the rear abutment 19; and the rear end of the bit holder engages this anvil member so that the rearward thrusts of cutting are transmitted to the abutment.

65 70 The anvil member may be made integral with the member 19; but it is preferred to form the anvil member as a replaceable unit. When so made, the anvil member is preferably provided with a rearward extension 21 engaging in a hole in the abutment member. If desired for alignment purposes, the rear end portion of the bit holder head 6 may be provided with a tooth 22 which can engage in a slot 23 in the anvil member.

The forward abutment 18 of the socket member is also provided with an anvil element 24. This is shown in Fig. 10 as a replaceable member having a forward lug or projection 25 adapted to fit into a perforation in the forward lug 18. The forward anvil member has a recess 26 in its rearward face to accept a forward face of the cutter bit. The slantwise wall of this recess exerts a wedging action on the bit, as will be evident, tending to urge the bit into the bit holder.

By these simple means, the bit holder of this invention is enabled to hold bits firmly during the cutting operation as well as to be slightly adjustable so as to accommodate bits, the dimensions of which are not always precisely the same due to the mode of manufacture. The rearward cutting thrusts on the bits are sustained largely by the rear abutment 19 of the socket member, while the inward or downward thrusts are sustained by the bit holder through the abutment means 7.

The particular mode of manufacture hereinabove outlined can be modified. It is possible to eliminate the drilling operation, thereby effecting further savings. One way of doing this is to effect an initial forging of the bit holder structure, as illustrated in Fig. 8, by means of a plunger 27 which forms the recess 11, as hereinabove described. The blank is then transferred to a second mold characterized by an orifice beneath the recess, and a second forging operation is accomplished by means of a plunger 28 having a nose 29 which will accomplish a piercing of the head behind the recess 11, as illustrated at 30 in Fig. 9. The piercing of the head provides clearance space for the unused bit point, as will be evident. Under some circumstances, it is possible to accomplish the entire forging operation in a single die with a single plunger. The use of two plungers and two molds will be indicated where the direction of motion of the two plungers is required to be different with respect to the axis of the recess 11.

Modifications may be made in the invention without departing from the spirit of it. The invention having been described in certain exemplary embodiments, what is desired to be claimed and secured by Letters Patent is:

1. A bit holder for a removable cutting bit having oppositely directed cutting points, the bit being substantially trapezoidal in side elevation, generally diamond shaped in central cross section and characterized by angularly related face planes at the sides of the trapezoidal conformation, said bit holder comprising an integral metal structure having a head and a shank, said head having a tapering recess of generally triangular transverse cross sectional shape formed therein from one side and adapted to receive a minor portion of the body of said bit in a position in which one of the said face planes of the said

bit lies along the base of the said triangular recess and another portion of the head within said recess contacts a portion of the said bit to hold the said bit downwardly with its said face plane in contact with the lower portion of the interior of said recess, whereby said bit is held against tilting so long as it is fully thrust into the said recess, there being a perforation of different cross sectional shape extending from the inner end of said recess through to the opposite side of said head to provide clearance for a cutting point of the said bit.

2. The structure claimed in claim 1 wherein said last mentioned perforation is a drilled hole larger in diameter than the inner end of said recess.

3. The structure claimed in claim 1 in which the base of said recess is formed with an upstanding flat abutment member to engage said one of said face planes of the cutter bit and sustain the inward thrusts of cutting.

4. The structure claimed in claim 1 formed by drop forging.

5. The structure claimed in claim 2 formed by drop forging.

6. A process of making cutter bit holders for trapezoidal bits which comprises drop forging a metal blank to provide a head and a shank, with a tapering recess formed therein from one side, said recess having a generally triangular cross-section, and providing a perforation of different cross-section meeting said recess from the opposite side of said head to provide clearance for the cutting point of a cutter bit a portion of the body of which is contained in said recess.

7. The process claimed in claim 6 wherein said perforation is formed by drilling.

8. The process claimed in claim 6 wherein said perforation is formed by piercing.

9. The process claimed in claim 6 wherein said recess is provided at its base with an upstanding flat abutment for engaging a face of a cutting bit to sustain the inward thrusts of cutting.

10. The process claimed in claim 9 wherein said perforation is formed by drilling.

11. The process claimed in claim 9 wherein said perforation is formed by piercing.
